Photographs (3 total) depicting various views of a Vaseline® Pure Petroleum Jelly jar and cap on sale in the USA by Chesebrough-Pond's USA Co., prior to Jan., 1993.

Primary Examiner—Lucy Lieberman
Attorney, Agent, or Firm—Milton L. Honig

[57] **CLAIM**

The ornamental design for a jar, as shown and described.

DESCRIPTION

FIG. 1 is a perspective view of the jar showing my new design;

FIG. 2 is a front elevational view of FIG. 1, the rear elevational view being the same;

FIG. 3 is a right side elevational view of FIG. 1, the left side elevational view being the same;

FIG. 4 is a top plan view of FIG. 1; and,

FIG. 5 is a bottom plan view of FIG. 1.

The broken line structures in FIG. 1 through FIG. 4 are for illustrative purposes only and form no part of the design.
